STOCKING

Otto C. Gehring, Montgomeryville, Pa., assignor to Lexington Hosiery Company, Inc., Hatfield,
Pa., a corporation of Pennsylvania

Application June 24, 1952, Serial No. 20,333

Term of patent 14 years

(Cl. D47—7)

To all whom it may concern:

Be it known that I, Otto C. Gehring, a citizen of the United States of America, residing at Montgomeryville, in the county of Montgomery and State of Pennsylvania, have invented a new, original, and ornamental Design for a Stocking, of which the following is a specification; reference being had to the accompanying drawing, forming part thereof.

In the drawing:

Fig. 1 is a side view of a stocking, showing my new design, as it appears when worn;

Fig. 2 is a fragmentary rear view of the stocking shown in Fig. 1, and

Fig. 3 is an enlarged perspective view of the stocking shown in Fig. 1 in flat folded condition.

I claim:
The ornamental design for a stocking, as shown.

OTTO C. GEHRING.
